UNITED STATES PATENT OFFICE.

CHARLES FELL, OF LORAIN, OHIO, ASSIGNOR TO NATIONAL TUBE COMPANY, OF PITTSBURGH, PENNSYLVANIA, A CORPORATION OF NEW JERSEY

APPARATUS FOR RIFLING PIPES OR TUBES.

1,033,568.

Specification of Letters Patent. Patented July 23, 1912.

Application filed June 18, 1909. Serial No. 502,937.

To all whom it may concern:

Be it known that I, CHARLES FELL, of Lorain, Lorain county, Ohio, have invented a new and useful Apparatus for Rifling 5 Pipes or Tubes, of which the following is a full, clear, and exact description, reference being had to the accompanying drawings, forming part of this specification, in which—

Figure 1 is a front elevation of my improved apparatus; and Fig. 2 is a sectional top plan view of the same, the section of the rifling rollers being on the line II--II of Fig. 1.

My invention relates to providing pipes or 15 tubes with spiral ribs, these being known as rifled tubes.

The object of the invention is to provide a simple and effective mechanism by which this rifling may be rapidly carried out.

20 In the drawing, in which I show a preferred form of my apparatus, 2 is a hollow frame containing six idle rifling rollers 3. These rollers are shown as spaced equally around the circle within the housing or 25 frame and set at the proper angle to give the desired pitch to the rifling or grooves in the pipe. I have shown the bearings for these rollers as radially adjustable by means of bearing screws 4. The housing 2 may be 30 secured upon any suitable foundation framing 5.

Beyond the rifling rollers I provide a pair 35 of pulling rolls 6, 6, these rolls being set at the same angle as the rifling rollers, in relation to the travel of the pipe through the apparatus. These rolls are skew rolls with grooved peripheries arranged to give a pass corresponding to the shape of the pipe. They are power driven through any suitable 40 connections and act to pull the pipe from the rifling rollers after it has entered their bite.

In starting the operation, the pipe or tube is forced forwardly through the rifling rollers by means of any suitable rear pushing 45 apparatus, until they enter the bite of the pulling rolls. As the tube passes through the rifling housing, and is acted upon by the

rifling rollers, it will be turned or revolved through a plane which will correspond to the angle at which the rifling rollers are set. 50 As soon as the tube enters the pulling rolls these being power driven will act to pull the pipe or tube through the rifling rolls and at the same time cause it to revolve in a plane conforming to the angle at which they are 55 set, which is the same as the angle of the rifle or spiral groove.

The advantages of my invention result from the simplicity of the apparatus and its rapid and effective action in carrying out the 60 rifling operation.

Changes may be made in the form and arrangement of the rifling rollers, and the means supporting the same as well as in the means for causing the travel of the pipe 65 therethrough while allowing its rotation, without departing from my invention.

I claim:—

1. In apparatus for rifling pipes or tubes, the combination with a series of rifling rolls 70 arranged to contact at a plurality of equidistant points on the periphery of the pipes or tubes in forming the rifling beads thereon said rolls being angularly adjustable to vary the pitch of the rifling formed on the pipes 75 or tubes, of means in front of said rifling rolls arranged to draw the pipes or tubes lengthwise between the rifling rolls.

2. In apparatus for rifling pipes or tubes, the combination with a series of rifling rolls 80 arranged to contact at a plurality of equidistant points on the periphery of the pipes or tubes in forming the rifling beads thereon, said rolls being angularly adjustable to vary the pitch of the rifling formed on the 85 pipes or tubes, of power driven feed rolls in front of the rifling rolls whereby the pipes or tubes are drawn lengthwise through the rifling rolls, said rolls being skewed and having a line contact with the pipes or tubes. 90

3. In apparatus for rifling pipes or tubes, the combination with a series of idler rifling rolls arranged to contact at a plurality of equi-distant points on the periphery of the

pipes or tubes in forming the rifling beads thereon, said rolls being angularly adjustable to vary the pitch of the rifling formed on the pipes or tubes, of feed rolls in front of the rifling rolls whereby the pipes or tubes are drawn lengthwise through the rifling rolls, said rolls being skewed and having a line contact with the pipes or tubes

and means for positively driving said feed rolls.

In testimony whereof, I have hereunto set my hand.

CHARLES FELL.
